REFRIGERATOR LATCH

Hugh Wallace, Evansville, Ind., assignor to
Servel, Inc., New York, N. Y., a corporation of
Delaware

Application August 8, 1945, Serial No. 609,567

5 Claims. (Cl. 292—255)

1

My invention relates to household refrigerators having a treadle-operated door latch.

A treadle for operating the door latch of a domestic refrigerator should be smooth and quiet in operation. Such a treadle should be connected to the door latch mechanism in such a manner that sufficient force may be transmitted through the treadle to unlatch the door and to cock the latch mechanism without producing undue strains in the latching mechanism or in the connections between the treadle and the latch mechanism. A foot treadle for unlatching the door of a household refrigerator should be mounted on the refrigerator and connected to the latch mechanism in such a manner that all moving parts of the treadle and of the connections between the treadle and the latch may be adjusted at the factory and thereafter remain in adjustment throughout the life of the refrigerator.

I have invented a treadle and connecting mechanism for unlatching a refrigerator door in which the treadle is pivotally mounted on the refrigerator in such a manner that there is no metal-to-metal contact in the moving parts of the mounting. There are no parts to wear or to lose their adjustment in the mounting; no loose joints to rattle; and no metal-to-metal contact to set up squeaking noises. The treadle is connected to the latch by means of yieldable connections which prevent undue strains from being applied to the latch; the connections remain in adjustment at all times and afford smooth and quiet operation.

The above and other objects and advantages of the invention are attained as set forth in the detailed specification taken with the accompanying drawings, in which:

Fig. 1 is a perspective view of a refrigerator cabinet illustrating one embodiment of my invention;

Fig. 2 is a broken verticle sectional view taken on line 2—2 of Fig. 3;

Fig. 3 is a horizontal sectional view through the base of the refrigerator cabinet showing the treadle supporting and mounting mechanism in top plan view;

Fig. 4 is a vertical sectional view through the treadle mounting taken on line 4—4 of Fig. 3;

Fig. 5 is a vertical sectional view taken on line 5—5 of Fig. 3;

Fig. 6 is a vertical sectional view of a yieldable connection between the treadle and latch;

Fig. 7 is a top plan view, partly in section, taken on line 7—7 of Fig. 6;

Fig. 8 is a broken front elevational view, partly in vertical section, of an adjustable connection

2 between the upper hook member 34 and the latch bolt 16a of Fig. 1;

Fig. 9 is a side elevational view of a part of the mechanism illustrated in Fig. 8;

Fig. 10 is a partial top plan view of the latch bolt and connecting means;

Fig. 11 is a horizontal sectional view taken on line 11—11 of Fig. 9;

Fig. 12 is a vertical sectional view of a modification of the yieldable connection illustrated in Fig. 6; and

Fig. 13 is a vertical sectional view of a second modification of a yieldable connection between the treadle and latch.

Referring now to the drawings, particularly to Fig. 1, 10 designates generally a household refrigerator provided with a hinged door 11 for gaining access to a food storage compartment 12, a closure member 13 for an apparatus compartment 14 and a supporting base 15. Door 11 is provided with a latch mechanism 16 including a latch bolt 16a. A latch keeper 16b is mounted on the door jamb. Any suitable type of latch mechanism may be used; however, I prefer to use a latch mechanism similar to that illustrated and described in the copending application of Arthur C. Shuart, Serial No. 582,732, filed March 14, 1945. Since the particular latch mechanism does not form a part of this invention, this mechanism will not be described. However, the disclosure of the aforementioned Shuart application may be considered as being incorporated in this application and, if desired, references may be made thereto for a detailed description of the latch mechanism.

35 A treadle 17 is positioned in front of base member 15 and traverses the entire front of the refrigerator cabinet beneath closure member 13. As shown in Fig. 3, treadle 17 is rigidly connected to an X-shaped brace or mounting member 18 by means of a pair of brackets 19. Mounting member 18, which is located within the base of the cabinet includes a pair of V-shaped channel members 18a and 18b, with channel member 18b notched to receive the channel member 18a and with the abutting surfaces of the two channel members welded or otherwise secured together as at 18c. As viewed in Figs. 2 and 3, the inner ends of mounting member 18 are mounted on opposite sides of the cabinet base 15 near the rear portion of the base.

In accordance with this invention, these mountings each include a bolt 20 provided with a square shank 21 which passes through a square opening in a recessed portion 22 of the cabinet base. A recessed nut 23 secures the bolt to the re-

cessed portion of base 15. A pair of yieldable rubber washers 24 are threaded on to bolt 20 with the top end portion of the channel member 18a sandwiched therebetween. A metal washer 25 is threaded on to bolt 20 between the lower rubber washer 24 and a lock nut 26. Lock nut 26 is provided with a locking insert 27. These mountings afford pivot or hinge connections between the mounting member 18 and the cabinet base. The mounting member is held slightly yieldable between the rubber washers; the angle through which the inner ends of the mounting member travels being relatively small the rubber washers will yield sufficiently for this travel and at the same time afford quiet non-wearing hinge or pivot connections.

Treadle 17 is provided with a decorative corrugated tread 28 formed of stainless steel or other suitable polished material and inclined upwardly from the front edge thereof at an angle of approximately 30° with the horizontal. A pair of brackets 29 provided with rubber cushions 29a are attached to the front of base 15 for limiting downward movement of the treadle. A tension or counter-balancing spring 30 is attached at one end to base 15 and at its opposite end to the mid-portion of mounting member 18. Treadle 17 is connected to the bolt 16a of latch mechanism 16 by means of a rod 31 having a horizontal hook 32 formed on the upper portion thereof, a rod 33 having a horizontal hook 34 formed on its lower portion, a vertical wire 35, a bell crank 36 and a horizontal wire 37.

In accordance with this invention, as shown in Figs. 2 and 6, rod 31, which is square in cross-section, is connected to treadle 17 by means of an adjusting nut 38 provided with a recess in the upper portion thereof. A lock washer 39 provided with a square opening fits within this recess and is held in place by a spring clip 40. A yieldable rubber washer 41 provides a cushion between the adjusting nut 38 and the upper surface of treadle 17. A compression spring 42 surrounds the lower portion of rod 31 and is held in position at its upper end by a washer 43 and at its lower end by a washer 44. Washer 44 is provided with a square opening and with a hexagonal recess adapted to receive a hexagonal nut 45 threaded on the lower end of rod 31. This yieldable connection between rod 31 and treadle 17 not only prevents excessive pull on the latch mechanism 16, but also provides a means whereby treadle 17 may be moved through a slight angle as the treadle is moved upward or downward. Rod 31 is guided in a square opening in a bracket 46 which, in turn, is welded or otherwise secured to the refrigerator cabinet. A leaf spring 47 supported by bracket 46 yieldably holds the hook portion 32 of rod 31 in proper position relative to the hook portion 34 of rod 33.

As shown, the lower right corner of door 11, as viewed in Fig. 1, is provided with a housing member 48 adapted to form a recess to receive the hook portions 32 and 34 of rods 31 and 33 respectively. Rod 33, the lower portion of which is square in cross-section, is guided in a sleeve 49 having a square passage formed therein. Sleeve 49, which is screw-threaded at its lower end, projects through an opening in the housing member 48 and is secured to the housing by means of a nut 50. The threaded portion of the sleeve and the opening in the housing member are formed with flat mating portions which prevent the sleeve from turning. Rod 33 is drilled to receive a horizontal pin 51 which contacts nut 50, limiting up-

ward movement of the rod. The upper end of rod 33 is screw-threaded to receive an elongate adjusting nut 52. A locking spring 53 is provided for locking the adjusting nut 52 on rod 33. Both ends of spring 53 are bent axially outward as at 53a, Figs. 8 and 9, with the upper bent portion fitting into an opening 52a in adjusting nut 52 and the lower bent portion fitting into one of four notches 49a in the upper surface of sleeve 49. In order to adjust nut 52 on rod 33 it is necessary to compress spring 53 so that either the upper bent portion disengages the opening 52a in the adjusting nut or the lower bent portion disengages a notch 49a of sleeve 49. When so disengaged, adjusting nut 52 may be adjusted through the necessary full turns and quarter turns by making use of any one of the four notches 49a in the upper surface of sleeve 49, Fig. 11. Adjusting nut 52 is formed with a socket 52c having a hardened washer 52b permanently secured to the upper portion thereof. Vertical wire 35 is provided with a hardened collar 35a at each end thereof. These collars are held on the wire by heading or peening over the ends of the wire, as at 35b. The lower end of wire 35 slides through the washer 52b and the upper end of this wire slides through a roller 36b in bell crank 36.

The bell crank 36 is formed with forked or bifurcated end portions 36a adapted to receive and rotatably support hardened rollers 36b. The side portions, 36c, of the bell crank are held together by a hub 36d and are welded or otherwise secured together as at 36e. The bell crank is pivotally mounted, as by a pivot pin 54, to a stationary bracket 56, which bracket is welded or otherwise secured to a cross channel 55, Figs. 1 and 2. As shown in Fig. 2, the lower portion of channel 55 is cut away to permit pivotal movement of the bell crank. Pivot pin 54 is secured in bracket 56 and prevented from turning by a spring clip 57, the ends of which clip are bent over the edges of the bracket. As stated above, the upper end of vertical wire 35 slides through an opening in the lower roller 36b of the bell crank. The right end of horizontal wire 37, as viewed in Fig. 8 slides through an opening in the upper roller 36b of the bell crank and is provided with a collar 37a and a headed portion 37b. The left end of wire 37 is so bent at 37c and 37d that it can be hooked over a pin 16c of latch bolt 16a. The left end of wire 37 is clamped to pin 16c by means of a clamp 58, a screw 59 and a nut 59a. Clamp 58 is formed with a pair of upstanding flanges which are cut away, as at 58a, so that the clamp is held in a definite position relative to the latch pin 16c.

In operation, when it is desired to open the door to the food storage compartment, the operator depresses treadle 17 by engaging any portion of the tread 28 with his toe, and even though pressure is applied inwardly as well as downwardly, the construction and arrangement of the tread, the yieldable connection between the rod 31 and treadle 17, the manner of mounting the treadle on the cabinet base and the long pivot arm of the treadle is such that the pressure is substantially all resolved into a downward vertical component. This downward pressure on the treadle causes the treadle to descend against the action of spring 30; downward movement of the treadle being limited by contact with cushions 29a. The compression of spring 42 is such that this spring does not yield appreciably when the treadle is first depressed. Therefore, as the treadle is depressed, rod 31 and at-

tached hook 32 are pulled vertically downward, causing rod 33 and attached wire 35 to be pulled vertically downward. This causes bell crank 36 to be rotated in a counter-clockwise direction as viewed in Fig. 1, pulling horizontal wire 37 to the left, thereby unlatching latch mechanism 16. Should an excess pressure be applied to the treadle after the latch mechanism has reached the end of its travel, compression spring 42 will yield thereby preventing undue strain from being applied to the latch mechanism. After the door has been opened and the operator has removed his foot from the treadle, the spring 30 and the rubber cushions 24 return the treadle and rod 31 to the position shown in Figs. 1 and 2, and in the meantime, spring 53 will have returned rod 33 to its uppermost position. To close the door it is only necessary for the operator to shove the door with sufficient force that the latch keeper, 16b, contacts and trips the latch mechanism 16, whereupon the latch mechanism draws the door into air-tight engagement with the cabinet, as fully explained in the aforementioned application of Arthur C. Shuart.

Referring now to Fig. 12 of the drawing, the treadle 17 is connected to the lower or threaded portion of a rod 31' by means of an adjusting nut 60. Rod 31' is generally similar to rod 31 of Figs. 1-7 except that the lower or threaded portion of rod 31' is round. As shown, adjusting nut 60 comprises a spool formed with an upper flange 60a, a lower flange 60b and an internally-threaded shank or connecting member 60c. A pair of yieldable rubber washers 61 are threaded on to the shank of the spool with the upper flat portion of treadle 17 sandwiched therebetween. The structure illustrated in Fig. 12 may be assembled by placing the upper rubber washer on the shank portion of the spool, the shank portion of the spool is then inserted into an opening in the upper flat portion of treadle 17, the bottom rubber washer is applied to the shank, the lower flange of the spool is applied to the shank and the lower portion of the shank is peened over the lower flange, as shown in Fig. 12. The rod 31' is then screwed into the spool until the proper length of the rod extends above the treadle, then the rod is mounted in the guide bracket 46. Because of the square cross-section of the upper portion of rod 31' and the rectangular opening in bracket 46, no further turning of rod 31' can occur. If, however, an adjustment finer than a complete turn of rod 31' is desired, the spool 60 may be turned upon the threaded portion of rod 31' to give any nicety of adjustment desired. A lock nut 62 is provided on rod 31' to prevent accidental turning of the spool relative to the rod. With the arrangement illustrated in Fig. 12, the treadle, which is cushioned between the rubber washers, can move through a slight angle without disturbing the vertical position of rod 31' and with the rod mounted in the above manner noise and wear are eliminated.

Referring now to Fig. 13 of the drawing, the rod 31'' is formed of two sections, a lower section 31a and an upper section 31b. These two sections are held together (shown separated in the drawing) under normal operation by a tension spring 70. The tension on spring 70 is such that when an excess pressure is applied to the treadle after the latch mechanism has reached the end of its travel, the two sections of rod 31'' will separate so as to prevent undue strain on the latch mechanism. Spring 70 includes a straight portion 71 at each end provided with a right angle bend 72. Each of the bent portions

72 fits into an opening 73 in each of the rod sections. A ferrule 74 is applied to each end of the spring to prevent the bent portions thereof from pulling out of the openings. The ferrules are held in place on the rod sections by center punch depressions 75 which project into the openings 73 opposite the bent portions of the spring. The upper portion of rod section 31a and the lower portion of rod section 31b is drilled to receive a guide pin 76, which pin holds the two sections of the rod in alignment as they move toward or from each other. The upper end of rod section 31b is provided with a horizontal hook (not shown) and the lower end of rod section 31a is provided with suitable means (not shown), but which may be similar to that shown in Fig. 12, for connecting this section to the treadle.

While I have illustrated and described specific embodiments of my invention, the invention obviously may take other forms and be variously applied within the scope of the following claims.

What is claimed is:

1. Latch mechanism for a hinged door of a cabinet including a latch bolt secured to said door, a treadle cushioned on said cabinet and having a tread traversing substantially the entire front of said cabinet below said door, and means yieldably connecting said treadle to said latch bolt, said means including a first vertical element yieldably connected to said treadle, a second vertical element connected to said first vertical element and passing upwardly through said door on the hinged side thereof and a horizontal element connected at one end to said second vertical element and at its opposite end to said latch bolt.

2. Latch mechanism for a hinged door of a cabinet, including a latch bolt secured to said door, a treadle mounted on said cabinet and having a tread traversing substantially the entire front of said cabinet below said door, means including rubber cushions for pivotally mounting said treadle on the bottom rear portion of said cabinet, and means operatively connecting said treadle to said latch bolt, said last-named means including a first vertical element yieldably connected to said treadle, a second vertical element connected to said first vertical element and passing upwardly through said door on the hinged side thereof and a horizontal element connected at one end to said second vertical element and at its opposite end to said latch bolt.

3. A latch mechanism for a door of a refrigerator cabinet including a latch bolt, a treadle positioned across the front of said cabinet and pivotally cushioned on two sides of said cabinet, means counter-balancing said treadle, means yieldably connecting said treadle to said latch bolt, said last-named means including a rod yieldably connected to said treadle and projecting upwardly therefrom and means mounted in said door operatively connected at one end to said rod and at its opposite end to said latch bolt.

4. A latch mechanism for a refrigerator cabinet having a door hinged thereto, said latch mechanism including a latch bolt mounted on said door, a treadle disposed at the lower portion of said cabinet and having a tread that traverses substantially the entire front of said cabinet below said door, rubber cushions pivotally mounting said treadle in the lower portion of said cabinet at two sides thereof, and means yieldably connecting said treadle to said latch bolt, said means including a bell crank, a rod connected to

said treadle; a vertical wire operatively connected at its lower end to said rod and slidably connected at its upper end to said bell crank and a horizontal wire slidably connected at one end to said bell crank and operatively connected at its opposite end to said latch bolt.

5. A latch mechanism for a refrigerator cabinet having a door hinged to one side thereof, said latch mechanism including a latch bolt mounted on said door, a treadle positioned across the front of said cabinet and pivotally mounted on two sides thereof, means counterbalancing said treadle, means connecting said treadle to said latch bolt, said last-named means including a rod operatively connected to said treadle and projecting upwardly therefrom, and mechanism mounted in said door operatively connected at one end to said rod and at its opposite end to said latch bolt, said mechanism including a bell crank, a vertical wire operatively connected at its lower end to said rod 20

and slidably connected at its upper end to said bell crank and a horizontal wire slidably connected at one end to said bell crank and operatively connected at its opposite end to said latch bolt.
